LAMP

Harry Eisenberg, Atlantic City, N. J.

Application March 30, 1950, Serial No. 8,882

Term of patent 7 years

(Cl. D48—20)

To all whom it may concern:

Be it known that I, Harry Eisenberg, a citizen of the United States, residing at Atlantic City, in the county of Atlantic and State of New Jersey, have invented a new, original, and ornamental Design for a Lamp, of which the following is a specification, reference being had to the accompanying drawing, forming part hereof.

In the drawing:

Fig. 1 is a front elevation of a lamp, showing my new design.

Fig. 2 is a side elevational view thereof,

Fig. 3 is a rear view thereof, and

Fig. 4 is a sectional view taken on line 4—4 of Fig. 1.

The dominant features of my design reside in the portions indicated by means of solid lines in the drawing.

I claim:

The ornamental design for a lamp, as shown and described.

HARRY EISENBERG.
